UNITED STATES PATENT OFFICE.

GAIUS C. MOORE, OF ROCHESTER, NEW YORK, ASSIGNOR TO JOHN C. MOORE CORPORATION, OF ROCHESTER, NEW YORK, A CORPORATION OF NEW YORK

LOOSE-LEAF BINDER.

1,018,770.

Specification of Letters Patent.

Patented Feb. 27, 1912.

Application filed August 11, 1911. Serial No. 643,534.

To all whom it may concern:

Be it known that I, GAIUS C. MOORE, a citizen of the United States, and a resident of Rochester, in the county of Monroe and

5 State of New York, have invented a new and Improved Loose-Leaf Binder, of which the following is a specification.

This invention relates to that class of loose leaf binders known as expansion binders, the object being to provide a construction permitting the use of leaves having closed holes rather than what are known as open slotted holes.

In carrying out my invention I may provide an expansion binder of any of the well known forms with an impaling post carrying plate hinged to one of the frame members, such plate carrying the usual telescoping impaling post members coöperating with 10 other impaling post members, telescoping therewith in the usual way, and carried by a second plate which may be removably secured to the opposite frame piece of the binder and, when thus secured to such opposite frame piece, the binder is operative by the expansion mechanism thereof in the usual way. When it is desired to insert or remove a leaf or leaves from the binder, the removable impaling post carrying plate 15 is unlocked and disengaged from the frame work of the binder, while the two impaling post carrying plates remain however in proper relative positions and with the posts carried thereby coöperatively telescoping 20 and engaging through the leaves in the binder; the impaling posts and the leaves thereon and the binder frame are then swung relatively to each other upon the hinged connection between the first named 25 impaling post carrying plate and the frame piece to which it is pivotally connected, after which the removable impaling post carrying plate can be removed with any desired number of the leaves in engagement over the 30 posts carried thereby, thus affording an opportunity for the removal or insertion of leaves at any desired point in the binder.

In the accompanying drawings, without however limiting myself in the application 35 of my invention to any particular style of construction of loose leaf binder, I have shown my invention as applied to an expansion loose leaf binder of the general style and construction shown and described in 40 United States Letters Patent #795,640, is-

sued July 25, 1905, to Henry J. Moore with only such changes therein as are called for or desirable to adapt the same to the embodiment of my invention therein.

The accompanying drawings illustrating 45 such a binder embodying my invention are as follows:

Figure 1 is a view of the back of the binder with the cover members and leaves removed. Fig. 2 is a sectional view taken 50 along the line $x-y$ of Fig. 1. Fig. 3 is a sectional view taken along the line $x'-y'$ of Fig. 1, but with the frame members moved relatively from each other. Fig. 4 is an end view of the parts shown in Fig. 1, but with 55 the frame members moved relatively from each other and with the impaling posts swung outwardly. Fig. 5 is a detail showing the means for locking the removable post carrying plate in the binder back. Fig. 6 is a detail view of the means for locking 60 the binder against expansion. Fig. 7 is a view, similar to Fig. 1, of the lower frame member seen in Fig. 1 and the posts carried thereby with the removable plate and posts 65 carried thereby shown removed from coöperative engagement with the posts on the hinged post carrying plate. Fig. 8 is an end view of the binder opened and with the removable plate and part of the leaves removed, the latter being shown in perspective and in reverse position in Fig. 9. Fig. 10 is a view of the member N from the under side with reference to Fig. 1.

Similar parts are designated by similar 70 reference characters throughout the several figures of the drawings.

Referring to the drawings, —B and B' are the frame members carrying flanges b which in turn carry the bosses c for the pivotal connection therewith of the cover-leaf sections in the usual way. The frame members B and B' have reinforcing end plates b formed integrally therewith. To the member B there is secured near each end thereof, 75 a rack R while to the member B' there are similarly secured racks R' . The racks R and R' are substantially similar in construction and conformation but are oppositely positioned whereby the teeth carried by 80 these racks are located on adjacent sides thereof with a space between them sufficient to receive in operative engagement the spur gears g secured on the operating shaft G extending longitudinally of the binder 85

and rotatably supported in bearings in the side walls of the rack incasing members D¹ extending upwardly from the back or bottom plate D of the binder.

- 5 The frame member B¹ is formed in two sections hinged together at h, the outer or upper portion having secured thereto the impaling post carrying plate V¹ carrying the posts v and t. The posts v are adapted 10 to telescope within tubular posts t carried by a second impaling post carrying plate V to which there are secured also the impaling posts v telescoping within the tubular posts t carried by the plate V¹.
- 15 On the shaft G there is provided a head m threaded and secured thereon as indicated in Fig. 1 and having projections thereon adapted to engage in suitable slots therefor in an operating key for turning the shaft 20 G, such members forming no feature of my present invention are only illustrated and mentioned herein as comprising parts of the binder described in said above mentioned patent to which my invention is in the present instance applied.

A metallic block N is fitted into the curved portion of the frame member B and is recessed at n to receive the head of the locking bolt P rotatably supported in the member N 30 and in a bracket A¹ carried by the frame member B¹. This locking bolt P has a series of ratchet teeth formed on one side thereof adapted to make locking engagement with the teeth formed on the adjacent upwardly 35 extending head a¹ of the bolt a, which is slidably supported in a seat in the housing A and actuated by the spring s, in the manner indicated, to make locking engagement with the ratchet teeth on the bolt P when such 40 bolt is rotated, to the position indicated in Fig. 1, with the teeth thereon opposite the end of the bolt a. The operation of these parts permits the side members B and B¹ to be forced together by the operation of the 45 rod G, in the manner clearly indicated, while the bolt a with the head a¹ thereon prevents a movement relatively apart of the side members B and B¹. When, however, the locking bolt P is rotated so that the teeth of the 50 ratchet thereon are moved out of engagement with the teeth on the head a¹ of the bolt a, the members B and B¹ may be moved relatively apart by the operation of the rod G, whereby, it will be seen that the binder 55 may be locked at any point in the relative adjustment of the members B and B¹.

The plate V is provided with an extension O as seen in Fig. 4 and shown in detailed face view in Fig. 5 and in this projection O 60 there is formed a slot o opening into a round hole of the diameter of the rod P to permit the rotation of such rod which, however, is notched on opposite sides to form a flattened portion for engaging within the slot o, when 65 the bolt P is turned to the position indicated

in Fig. 6, thereby permitting the plate V to be raised or lowered, but, when such bolt P, engaging through the opening therefor in the extension O on the plate V, locks such plate V in its normal position in the binder 70 it will be seen that the locking bolt P also locks the binder to prevent the relative movement of the members B and B¹.

In using the binder the bolt P is operated by a suitable key engaging the squared off 75 head thereof, and within the recess n therefor formed in the frame member B and in the block N, such key is turned to rotate the rod P to the position indicated in Fig. 6, when the plates V and V¹ with the impaling 80 posts carried therewith may be swung outwardly as indicated in Fig. 4. The plate V may then be removed to permit the insertion or withdrawal of leaves after which the plate V is forced to its normal position in 85 the binder with the leaves engaged by the impaling posts v and t, after which the bolt is again operated and turned to its locking position holding the plate V in its normal position and also locking the binder. Be- 90

fore turning the bolt P to its locking position the rod G may be operated by means of a suitable key, as above described, to force the members B and B¹ together where they are positively held by the coöperation be- 95

100 between the teeth on the locking rod P and the teeth on the head a¹ of the spring actuated locking bolt a.

The locking bolt P is prevented from a longitudinal movement by means of the collar p¹ and the quadrant p both of which are secured on the bolt P, the collar p¹ being seated in the cut out portion n of the block N while the quadrant p engages against a lug n¹ on the inner side of the member N, 105 the position of such lug being shown in Fig. 10. The lug n¹ engages within the slot o in the extension O in the plate V.

In Fig. 8 there is shown a binder with 110 cover leaves C and C¹ attached and leaves S on the impaling posts carried by the hinged plate V¹ which is swung outwardly, while the post carrying plate V and posts v and t carried thereby are shown removed with a 115 quantity of leaves seen thereon in reverse position in Fig. 9.

It is believed from the foregoing description that the method of operation and use 120 of my binder is sufficiently clear to call for no further explanation herein.

What I claim is:

1. In a loose leaf binder in combination with the frame members and the operating means for moving the same relatively to and from each other, an impaling post carrying plate hinged to one of said side members and a second plate carrying impaling posts adapted to telescope with the posts carried by the first plate to hold the leaves in the binder, such second plate removable from 125 130

the binder and from its coöperative position relative to the first plate and means for locking the second impaling post carrying plate in operative position in the second side 5 member of the binder.

2. In a loose leaf binder in combination with the frame members and the operating means for moving the same relatively to and from each other, an impaling post carrying 10 plate hinged to one of said side members and a second plate carrying impaling posts adapted to telescope with the posts carried by the first plate, such second plate removable from the binder and from its coöperative 15 position relative to the first plate and means for locking the second impaling post carrying plate in operative position in the second side member of the binder, such locking means comprising also means for locking 20 the side members of the binder against movement relatively from each other.
3. In a loose leaf binder in combination with the frame members and the operating means for moving the same relatively to and 25 from each other, an impaling post carrying plate hinged to one of said side members and a second plate carrying impaling posts adapted to coöperate with the posts carried by the

first plate to hold the leaves in the binder, such second plate removable from the binder 30 and from its coöperative position relative to the first plate and means for locking the second impaling post carrying plate in operative position in the second side member of the binder. 35

4. In a loose leaf binder in combination with the frame members and the operating means for moving the same relatively to and from each other, an impaling post carrying plate hinged to one of said side members and 40 a second plate carrying impaling posts adapted to coöperate with the posts carried by the first plate to hold the leaves in the binder, such second plate removable from the binder and from its coöperative position 45 relative to the first plate and means for locking the second impaling post carrying plate in operative position in the second side member of the binder, such locking means comprising also means for locking the side members of the binder against movement relatively from each other. 50

GAIUS C. MOORE.
